United States Patent Office.

WILLIAM G. KELLY, OF ONEIDA, NEW YORK.

Letters Patent No. 96,442, dated November 2, 1869.

IMPROVED CASE AND SAMPLE-CARD FOR SPOOLED SILK, &c.

The Schedule referred to in these Letters Patent and making part of the same.

To all whom it may concern:

Be it known that I, WILLIAM G. KELLY, of Oneida Community, Oneida, Madison county, State of New York, have invented a new and useful Improvement in Combined Show-Case and Sample-Card for Spooled Silk, &c.; and I do hereby declare that the following is a full, clear, and exact description thereof, whereby those skilled in the art can make and use the same, reference being had to the accompanying drawings, forming part of this specification.

Figure 1 is a top view of my improved show-case when opened to display its contents.

Figure 2 is an end view of the same, part being broken away to show the construction.

Figure 3 is a cross-section of the same when closed.

My invention has for its object to furnish an improved show-case, which shall be so constructed and arranged as to hold the spools securely in place during transportation, exhibit them to good advantage, to display the variety of colors, and at the same time allow the spools to be conveniently taken out; and

It consists in the construction, combination, and arrangement of various parts of the case, as herein-after more fully described.

A represents the lower part or bottom, and B, the upper part or cover of the case.

The bottom and cover A B are hinged together at the edges of their rear sides, as shown.

The forward side and ends, in whole or in part of the part A, project above the plane of the edge of the rear side, to form a seat for the tray, till, or drawer, G.

The lower part A, of the case, is divided into compartments by transverse partitions a', and should be of such a depth as to contain two rows of spools, placed one upon the other.

The partitions a' should be at such a distance apart that the compartments may equal in breadth the length of the spools to be placed in them.

D are stops, attached to the middle of the sides of the partition a', and which are made of a breadth equal to the space not taken up by the spools, to prevent the spools from shaking about, and at the same

time allow them to be conveniently removed, by inserting the finger between said stops.

The upper edges of the partitions a' have the numbers or names, either or both, of the color of silk or thread placed in that compartment, stamped or otherwise placed upon them, so as to serve as a sample-card to order from.

In case numbers only are placed upon the partitions a', the same numbers and the corresponding names may be placed in the cover B, to serve as a schedule for convenient reference.

C is the sliding till, tray, or drawer, which is divided up into compartments by transverse partitions, provided with stops, in the same manner as the lower part of the case, hereinbefore described.

The tray C is placed in the lower part of the case, above the partitions of said lower part, and is made of such a height as to rise above the upper edges of said part and enter the cover B where the case is shut. This construction confines the air when the case is shut quickly, which confined air serves as a cushion, to prevent the cover from shutting with a slam.

The tray C slides back and forth from the part A to the cover B, stops b' being attached to the sides of said cover, to support the said tray when sliding back and forth, and when standing in the said cover B, to display the silk or thread.

E is a bracket, attached to the forward part of the top of the cover B, to serve as a support to hold the said cover in proper position when turned back, and also to serve as a handle for opening the case.

Having thus described my invention,

I claim as new, and desire to secure by Letters Patent—

A show-box for spooled silk, provided with case A B, handle E, transverse partitions, anti-rolling separators D, and tray C, each of said parts being constructed and arranged with respect to the others, in the manner described.
